Ernest W. Worley, Kansas City, Kans., assignor to Consolidated Razor Blade Co. Inc., Jersey City,
N. J., a corporation of New Jersey

Application October 10, 1940, Serial No. 95,750

Term of patent 7 years

To all whom it may concern:

Be it known that I, Ernest W. Worley, a citizen of the United States and a resident of Kansas City, Wyandotte County, State of Kansas, have invented a new, original, and ornamental Design for a Flashlight or Similar Article, of which the following is a specification, reference being had to the accompanying drawing, forming a part thereof, in which:

light showing my new, original and ornamental design;

Fig. 2 is a side elevational view thereof;
Fig. 3 is a top plan view thereof; and

Fig. 4 is a rear elevational view thereof.

I claim:

The ornamental design for a flashlight or similar article, as shown.

E. W. WORLEY.
